UNITED STATES PATENT OFFICE.

WALTER T. ROSS, OF QUEBEC, QUEBEC, CANADA.

THILL-COUPING.

SPECIFICATION forming part of Letters Patent No. 402,974, dated May 7, 1889.

Application filed August 30, 1888. Serial No. 284,205. (No model.)

To all whom it may concern:

Be it known that I, WALTER T. ROSS, of the city, county, and Province of Quebec, in the Dominion of Canada, have invented certain new and useful Improvements in Thill-Couplings; and I do hereby declare that the following is a full, clear, and exact description of the same, reference being had to the accompanying drawings, in which—

10 Figure 1 is a top view of my improved thill-coupling. Fig. 2 is a side elevation of the same, and Fig. 3 is a plan of Fig. 1 inverted. My invention relates to that class of thill-couplings in which two jaws are hinged together by the rear leg of a clip which secures the thill-coupling to the axle of the vehicle, said jaws opening apart to receive the thill-iron intermediately and a coupling-bolt passing through the thill-iron and jaws; and the 15 object of my present invention is to prevent rattling of the the thill-iron when the jaws are closed against the thill-iron and the bolt screwed to tighten the same, and also to diminish frictional wear at the joint and to take 20 up looseness resulting therefrom.

25 My invention consists of a thill-coupling having two jaws hinged together at the rear end to be both movable apart, and means for securing the same to the axle, the front end of 30 said jaws having a coniform projection, the smaller ends opposite to one another and having holes in alignment horizontally to receive a coupling-bolt, and a thill-iron having a bore to receive the coupling-bolt, said bore conically enlarged at both ends to admit the cones of the jaws, so that by tightening the coupling-bolt the cones will be drawn inwardly to take up wear of the thill-iron, and thereby 35 prevent rattling.

40 1 is the axle of the vehicle; 2, the clip; 3, the coupling-bolt, and 4 the thill-iron, having a bore parallel to the axle to admit the coupling-bolt.

45 5 6 are the coupling-jaws, hinged together at the rear end by the rear leg of the clip passing through a hole in the jaws and through a

hole in plate 7 under the jaws, said leg provided with a nut, 8, which supports said plate when clipped to the axle. The other leg of the clip passes between said jaws and through 50 plate 7 and is provided with a nut, 9, said plate underlying the jaws, and the nut supports the same when clipped to the axle of a vehicle.

55 As both jaws are movable to admit the thill-iron interveningly, the coupling-bolt will be parallel to the axle, thus avoiding straining of the thills to effect coupling. The outward or forward end of the jaws 5 6 are provided with a coniform projection, 10, from the inner 60 face of the jaws and integral therewith, so that the two small ends will point toward each other. The jaws and projections therefrom have holes in alignment to receive the coupling-bolt 3, and the bore of the thill-iron is 65 conically enlarged at both ends to coincide with the coniform projection 10 of the jaws. When coupling, the jaws are opened apart to admit the thill-iron and again closed, the coniform projections then entering the conically- 70 enlarged bore of the thill-iron. The coupling-bolt is then passed into the holes in the jaws and projections and thill-iron and nut 13 on the coupling-bolt screwed up to tighten the coniform projections in the coinciding bore 75 of the thill-iron.

I claim as my invention—

80 The combination of the axle-clip 2, the movable jaws 5 6, having inwardly-facing coniform projections 10 at the forward end and hinged together at the rear by one leg of the clip, the other leg intervening the jaws, the plate 7, supporting said jaws and bearing on the clip-nuts, the thill-iron 4, having a bore conically enlarged at both ends, and the coupling-bolt 85 3, passing through the bore of the coniform projections and thill-iron and provided with a nut, 13, at the end, as set forth.

WALTER T. ROSS.
